WASHING APPARATUS

Frank Breckenridge, Mansfield, Ohio, assignor to
 Westinghouse Electric & Manufacturing Company, East Pittsburgh, Pa., a corporation of Pennsylvania

Application April 23, 1938, Serial No. 203,805

15 Claims. (Cl. 68—23)

My invention relates to apparatus for washing fabrics or the like and has for an object to provide improved apparatus of this kind.

It is a further object of the invention to provide improved means for agitating the washing fluid in a laundry machine and for spinning the fluid from the fabrics being washed.

A further object of the invention is to provide an improved washing machine wherein agitation of the washing fluid is effected in a container structure that may be rotated for discharging the fluid therefrom and for the extraction of fluid from the fabrics being washed.

A further object of the invention is to effect agitation of the washing fluid in a container by means, rotating unidirectionally, and to centrifugally discharge the fluid from the container and the fabrics therein by rotating the container.

A further object of the invention is to provide combined washer and spinner wherein the fabrics being washed are uniformly distributed in the container when the spinning operation is initiated.

A still further object of my invention is to automatically effect, in a predetermined sequence, the various steps in a washing program, including the extraction of washing fluid from the fabrics by centrifugal action.

Another object of the invention is to reduce vibration in a washing machine employing centrifugal action for the extraction of washing fluid from its contents.

It is another object of the invention to provide an improved laundry machine in which the amount of water admitted thereto is not critical to efficient operation.

These and other objects are effected by my invention, as will be apparent from the following description and claims taken in connection with the accompanying drawings, forming a part of this application, in which:

Fig. 1 is a vertical sectional view of my improved washing apparatus and is taken along the line I—I of Fig. 2;

Fig. 2 is a plan view of the apparatus shown in Fig. 1 with the top panel removed and other portions broken away for the sake of clearness;

Fig. 3 is a vertical sectional view taken along the line III—III of Fig. 2, with certain portions shown in elevation;

Fig. 4 is a sectional view taken along the line IV—IV of Fig. 2;

Fig. 5 is a sectional view of the speed reducing mechanism and is taken along the line V—V of Fig. 1;

Fig. 6 is a sectional view of a detail shown in Fig. 3; and

Fig. 7 is a diagram of the electrical connections which may be employed when the apparatus is operated automatically for effecting a predetermined series of steps in a washing program.

Reference will now be had to the drawings wherein I have shown my invention applied to a domestic type washing machine including a basket or tube structure 10 having an imperforate bottom portion 11 and a plurality of fluid discharge openings 12 circumferentially spaced in an upper portion of the side wall 13 thereof for a purpose to be referred to hereinafter. The side wall 13 preferably tapers outwardly and upwardly as shown and includes an inwardly extending flange portion 14 that defines an access opening 15 at the top of the basket. The basket 10 is preferably maintained stationary during washing periods and, as described hereinafter, is rotated during drying or spinning periods. Accordingly, the basket 10 is journaled, preferably, on the exterior of a vertical cylindrical column 16 that is carried by a cradle structure 17 disposed below the basket. The basket 10 and its supporting cradle structure 17 are enclosed in a casing generally indicated at 18 and including a frame 19 and finishing side panels 21 secured thereto. The casing 18 also includes a top panel 22 having an opening 23 formed therein and aligned substantially with the opening 15 in the basket 10. The opening 23 provides access to the basket for the insertion and removal of the articles to be washed.

As is more fully described hereinafter, agitation of the washing water is provided by a pump 24 disposed in the bottom of the basket 10 and including an impeller 25 of suitable form and disposed within a pump casing 26. The latter is secured to the basket 10 and is provided with a plurality of fluid inlet openings 27. A substantially horizontal partition 28 is disposed in the bottom portion of the basket 10 and defines a sump 29 from which water passes to the inlet openings 27 of the pump casing 26. The partition 28 forms the bottom of a washing chamber 31 and prevents the articles being washed from gravitating to the sump 29. Preferably, the inner portion of the partition is imperforate and its outer portion is provided with a plurality of passages 32 for permitting fluid to pass from the washing chamber 31 to the sump 29.

The pump casing 26 includes a portion 26A that extends above the partition 28 into the washing chamber 31 and provided with radially

extending fluid discharge openings 33 above the partition 28. The upper portion 26A of the pump casing 26 forms a centrally disposed cone 34 within the washing chamber 31 which cone may be hollow as shown. The interior of the cone 34 may be closed by a suitable closure or cap 34A for preventing admission of water to the interior of the cone. During operation of the washer, the impeller 25 is rotated by a shaft 35 that is preferably directly connected to a motor 36, the latter being carried by the cradle structure 17. The shaft 35 is journaled within the center column 16. Any suitable form of bearings may be employed for rotatably supporting the basket 10 and the shaft 35, but I prefer to use anti-friction bearings shown at 37 and 38, respectively. A conventional seal 39 may be employed for preventing leakage of water from the pump casing 26 to the bearing 38. The seal 39 may be carried by an inwardly extending web 40 formed in the bottom of the pump casing 26 and covering the bearings 37. The washing action produced by the impeller pump 24 will be described in detail hereinafter.

As stated heretofore, the basket 10 is rotated for the purpose of discharging the washing fluid therefrom and for the extraction of fluid from the articles being washed. The mechanism for effecting rotation of the basket will now be described.

Rotation of the basket 10 is effected by the motor 36 and, preferably, at a lower speed than the speed of the impeller shaft 35 so that a speed reducing mechanism 41 is interposed between the shaft 35 and the basket. The speed reducing mechanism 41 may include a relatively slow speed element or sleeve 42 that is journaled on the cylindrical column 16. The sleeve 42 drives the basket 10 through a clutch 43, the latter being shown of the cone type but which may be of any other suitable construction. The driving element of the clutch 43 is shown at 44 connected to the sleeve 42 and the driven element 45 of the clutch 43 is splined to a hub 46 secured to the underside of the basket 10. As shown, the hub may be formed integral with the pump casing 26 and it is between the hub 46 and the cylindrical column 16 that the anti-friction bearings 37 are arranged.

Operation of the clutch 43 may be effected in any suitable manner when the washing apparatus is operated as a non-automatic machine. As a washer constructed in accordance with my invention is particularly adaptable for automatic operation wherein a predetermined program of steps is effected cyclically, I have chosen to disclose it as an automatic washer. Accordingly, the movable or driven clutch element 45 is actuated electrically, preferably, by an electro-magnet 47 having a winding 48 and a movable armature 49. The latter may be connected to a bell crank 51 pivoted at 52 and having an arm 53 for actuating the driven element 45 of the clutch 43. Movement of the arm 53 may be imparted to the clutch element 45 by means of pins 54 secured in the arm and extending into an annular groove 55 formed on the clutch element 45. The clutch 43 is biased to its open position by suitable means, such as a torsion spring 56 which urges the bell crank 51 in clockwise direction about its pivot 52. Energization of the magnet winding 48 attracts its armature 49 and effects counter-clockwise movement of the bell crank 51 whereby the clutch element 45

is moved axially into engagement with the driving element 44 of the clutch 43.

Deceleration of the basket 10 may be effected by a brake, generally indicated by the numeral 57 and including a stationary member 58 secured to the cradle 17, and an annular face 59 formed on the driven element 45. When the clutch is moved to its open position, as shown, the face 59 of the driven element 45 engages the stationary braking member 58 and deceleration of the driven clutch element 45 and the basket 10 splined thereto is effected.

The employment of the brake 57 to maintain the basket 10 stationary is optional. It may be desirable to permit slow rotation or oscillation of the basket by the agitated body of water therein during washing periods as it has been found that such operation improves the washing action in certain types of washers. This is due to the shifting of the body of fluid and the fabrics therein relative to the agitator means, and, therefore, the more even distribution of the work done by the agitator.

The driven sleeve 42 of the speed reducing mechanism 41 may be provided with an internal gear 63 disposed within a gear chamber 64 and driven by a pinion 65 through idler gears 66 and 67, see Fig. 5. The pinion 65 is driven by the shaft 35 at relatively high speed, for example, 1750 R. P. M. and the speed reduction is such that the sleeve 42 is operated at approximately 500 R. P. M. Preferably, the sleeve 42 and shaft 35 rotate in the same direction. As will be more apparent from the description which follows, the sleeve 42 and shaft 35 rotate at all times that the washer is operated.

The cylinder column 16 which defines the support for the basket 10 may be secured in position by bolts 68 which are threaded in a flange 69 formed on the bottom of the column 16. The bolts 68 secure the column 16 to a cover 71 carried by the cradle structure 17 and closing the gear chamber 64. The flange 69 is cut away for providing a recess 72 for the idler gears 66 and 67 as best shown in Fig. 5. The bolts 68 which extend through the recess 72 may define axles for the idler gears 66 and 67.

A steady bearing 73 for the lower end of the impeller shaft 35 is carried by the cover 71. A gland or stuffing box 74 may be employed for preventing the loss of lubricant from the gear chamber 64, the gland being disposed below the bearing 73 as shown.

The motor 36 for actuating the impeller 25 and the basket 10 is carried by brackets 75 which depend from the cover 71. A conventional coupling 76 may be employed for connecting the shaft of the motor 36 and the lower end of the impeller shaft 35.

The specific form of speed reducing and clutch mechanism which I have disclosed forms no part of the present invention and illustrates but one of many mechanisms which may be employed for effecting relatively high speed operation of the impeller shaft 35 and intermittent lower speed operation of the basket 10 about a common axis.

The supplying of water to the basket may be effected in any suitable manner. As shown in Fig. 3, a pair of conduits 77 and 78 are provided for connection to respective hot and cold water sources. The hot and cold water commingle in a mixing chamber 79 which is connected by a conduit 81 to a discharge nozzle 82, the latter overhanging the basket 10. Water discharged from the nozzle 82 enters the basket 10 through

its opening 15, and is preferably directed by the nozzle 82 toward the center member 34. An over-flow opening 80 may be provided in the side wall 13 of the basket for preventing overfilling of the basket, which opening 80 is slightly above the normal water line.

Sufficient structure has now been disclosed to describe the washing action which is effected in the basket 10. Water and a detergent, such as soap are admitted to the basket 10, the normal level of the fluid being indicated by the broken line. The articles or fabrics to be washed are placed in the fluid and the motor 36 is energized. During washing periods, the clutch 43 is open so that the basket 10 is substantially stationary. The motor 36 operates to rotate the impeller 25 whereby fluid from the sump 29 is drawn into the pump casing 26 through the openings 27 and discharged at relatively high velocity through the discharge openings 33 into the bottom of the washing chamber 31. The discharged fluid passing over the partition 28 induces outward movement of the body of fluid in the bottom of the washing chamber 31. Some of the fluid passes through the openings 32 to the sump 29 but the majority of the fluid after moving radially over the partition 28 moves upwardly within the tapered wall 13 of the basket 10 and thence inwardly towards the cone 34 at the center of the basket. The fluid then descends adjacent the cone 34 and is again motivated by the fluid discharged from the openings 33. The movement of the turbulent fluid in the basket is shown by the arrows in Fig. 1.

The fabrics in the basket are carried by the fluid and agitated therein, the soils in the fabrics being removed by the detergent fluid after a period of operation, the duration of which depends upon the condition of the soils. The method of cleansing fabrics described heretofore is well understood in the art so that further description of the same is deemed unnecessary.

In accordance with my invention, the basket 10 is rotated for discharging the water therefrom and for extracting a substantial portion of the water from the clothes. This operation is effected after the washing operation is completed. Engagement of the clutch 43 initiates rotation of the basket 10 by the motor 36 through the speed reducing mechanism 41. As the basket 10 accelerates, the fluid therein moves outwardly and upwardly due to centrifugal action and passes through the discharge openings 12. A baffle 83 of cylindrical configuration surrounds the basket and is engaged by the fluid projected through the openings 12. Fluid draining from the baffle 83 is collected in an annular trough or pan 84 disposed below the lower edge of the baffle 83 and supported by the cradle structure 17. Fluid is discharged from the pan 84 in any suitable manner, such as, for example, by means of a pump 85 driven by the motor 36. A conduit 86 connects the pan 84 with the inlet of the pump 85 and a second conduit 87, such as, for example, a flexible hose, conveys the fluid from the pump to a point of discharge.

The fabrics are maintained in a separated and loose condition during the washing operation so that they are distributed in the basket uniformly. When rotation of the basket is initiated, the fluid and fabrics move outwardly and, after the main body of fluid has been discharged, the fabrics are deposited in a substantially uniform condition about the inner wall of the basket 13. Rotation of the basket extracts fluid centrifugally from

the fabrics, which fluid flows upwardly within the tapered side wall 13 of the basket 10 and is discharged through the openings 12. Clear water may be supplied at this time through the nozzle 82 for providing a spray rinse whereby a portion of the soap remaining in the fabrics is dissolved and carried away by the rinse water. Vibration which is caused by an unbalanced load during the spinning operation is reduced to a minimum by the more even distribution of the fabrics in the basket 10. This feature of my invention is particularly desirable when employed in a washer operating automatically wherein the transition from the washing step to the spinning or fluid extracting step is effected without manual attention.

After the washing and spinning of the fabrics has been completed, final rinsing of the fabrics is effected. The operation of the apparatus is the same as described heretofore except that rinse water is used instead of water and a detergent. The clear rinse water may be circulated and agitated by the pump until substantially all of the soap diffuses in the water and is discharged when spinning of the basket is effected.

The washing and spinning structure, described heretofore, may be flexibly mounted within the casing structure 18 for reducing vibrations imparted to the latter, particularly during the extracting or spinning periods. Any suitable mechanism may be employed for flexibly mounting the washer structure. The supporting mechanism may include a pair of vertical tubular members 91, the lower ends of the tubular members 91 being secured to and carrying the cradle structure 17. The tubular members 91 are suspended from a gimbal ring 92, the latter encompassing the baffle 83 in spaced relation. Oppositely disposed bearings 93 are provided in the gimbal ring for receiving studs 94 projecting from the tubular members 91. The gimbal ring 92 is provided with oppositely disposed hubs 95 that are supported in bearings 96 in equalizer bars shown at 97, which hubs 95 are spaced 90° from the studs 94 carried by the vertical members 91.

The equalizer bars 97 are carried by vertical connecting rods 98 which are supported by the frame 19. Ball and socket connections 99 are provided between the connecting rods 98 and the frame 19 and between the connecting rods 98 and the equalizer bars 97. A pair of inertia stabilizers 101 may be carried by the vertical members 91 adjacent the top thereof, the stabilizers 101 defining a support for the baffle 83.

It will be apparent from the foregoing description that the connecting rods 98 and the equalizer bars 97 define the sole support for the gimbal ring 92, the latter carrying the vertical members 91, the cradle structure 17 and the apparatus supported thereby. Rocking movement of the rotating elements of the washer in vertical planes normal to each other is provided by the pivotably mounted gimbal ring 92 and the pivoted connection between the ring 92 and the vertical tubular members 91. Movement of the gimbal ring 92 horizontally is provided by the connecting rods 98 and their ball and socket connections 99 to the equalizer bars 97 and the casing structure 18. Accordingly, the vertical axis of the basket 10 is free to shift horizontally in any direction and may rock in any vertical plane.

Movement of the flexibly mounted structure

is opposed by its mass. The amplitude of movement of said structure for a given unbalanced load may be maintained within predetermined limits by varying the mass of the inertia stabilizers 101. Vibration of the casing structure 19 is eliminated, substantially, by the flexible mounting of the rotating elements and their supporting structure so that the washer may be constructed as a portable machine and operation of the same effected without any special foundation provisions or securing the casing to the laundry floor.

As mentioned heretofore, my improved washer is particularly adaptable for automatic operation wherein washing, rinsing and spinning of the fabrics being cleansed are automatically effected for predetermined periods of time. The apparatus may readily be adapted for automatic operation because of the simplified mechanism for effecting the washing of the fabrics, the discharge of water from the apparatus and the extraction of water from the fabrics. The only automatic operation necessary during transition from the washing period to the water discharging and extraction periods is the adjustment of the clutch 43 between the driving motor 36 and the basket 10. No clutching operation is necessary for the impeller 25 as it is continuously operated during all periods that the apparatus is active. A description of the apparatus for automatically effecting a predetermined program of steps in the cleaning of fabrics follows.

When arranged for automatic operation, the flow of hot and cold water from the conduits 71 and 78 to the mixing chamber 79 is controlled by respective electrically operated valves 103 and 104. The valves 103 and 104 may be actuated by solenoids 105 and 106, respectively. As the construction and operation of such valves is well known in the art, further description of them is deemed unnecessary other than to state that they are open when their solenoids are energized and are closed when the solenoids are deenergized. The motor 36, and solenoids 105 and 106 and the clutch magnet winding 48 are energizable from a suitable source of power represented by line conductors L₁ and L₂ in Fig. 7.

Reference will now be had to the electrical diagram (Fig. 7), wherein I have shown a time control mechanism 107 including a drum switch 108 driven by a motor 109 of the type commonly employed for operation of clocks. The drum switch 108 is shown in development and includes a plurality of stationary contact fingers 109 to 112, inclusive, and a drum 113 having a plurality of electrically connected movable segments 113 to 117, inclusive, cooperating with said fingers. A shaft 118 of the drum switch is driven by the motor 109 through a speed reducing mechanism 119. It will be understood that the developed drum 108 moves in the direction indicated by the arrow when actuated by the shaft 118. The drum switch 108 is provided with a handle or knob 121 for moving the drum 108 manually when starting its operation. A suitable slip clutch 122 may be provided between the drum shaft 118 and the speed reducing mechanism 119 which permits manual rotation of the drum by the knob 121 and which drives the drum 108 when the motor 109 is operated.

Temperature control of the water admitted to the basket 10 may be provided by a thermostat 123 including a switch 124 connected in circuit with one of the valve solenoids. As shown, the switch 124 is in circuit with the cold water valve 75

solenoid 106. The thermostat 123 may include a snap acting bimetallic member 125 disposed in heat transfer relation with the water in the mixing chamber for actuating the switch 124. 5 When the temperature of the water in the mixing chamber 79 is below a predetermined value, the bimetallic member holds its switch 124 open so that the cold water solenoid is deenergized and only hot water is delivered to the mixing chamber 79. As the temperature of the water increases to a second value, the bimetallic element closes the switch 124 so that the solenoid 106 is energized and cold water is delivered to the mixing chamber for mixture with the hot water.

Adjustment of the thermostat 123 may be provided for varying the temperature of the water delivered to the basket 10. This feature is desirable as different fabrics require different wash water temperatures. In order to vary the water temperature, at which the switch 124 is opened, a small heater 126 may be provided for the bimetallic element 125, which heater 126 is controlled by a temperature selector switch 127. When the heater 126 is energized, the bimetal element 125 is subjected to heat from both the heater 126 and the water so that it operates the switch 124 to maintain lower water temperatures in the mixing chamber 79. It will be understood that the water temperature adjusting means which I have disclosed is shown by way of example and that various other means may be employed for effecting adjustment of the water temperature.

One form of thermostat 23 which may be employed is structurally shown in Fig. 6. A relatively thin plate 131 having high heat conducting properties is secured to the wall of the mixing chamber 79 and covers an opening formed in the wall so that the water in the mixing chamber 79 is in contact with the plate 131. The thermostatic element 125 is secured to the plate 131 in heat transfer relation therewith. Accordingly, temperature changes in the water are quickly reflected by the thermostatic element 125. Stationary contacts 132 and 133 of the switch are shown carried by an insulating cover 134 which is recessed for housing the thermostatic element 125. A movable contact 135 is actuated by the thermostatic element 125 and bridges the contacts 132 and 133 in the closed position of the switch 124. The heater 126 is shown secured to the thermostatic element in heat transfer relation therewith. The conductors that are connected to the contacts 132 and 133 and the heater 126 are shown diagrammatically and enter the recess of the cover 134 through an opening 136.

The temperature selector switch 127 and the motor driven time switch 107 may be carried on 60 one of the side panels 21 of the casing structure 18 where they are accessible to the operator, (see Fig. 2).

Operation

A description of the automatic operation of my improved washing apparatus will now be given. The fabrics to be cleansed and a detergent, such as, for example, soap, are deposited in the basket 10 and the operator adjusts the temperature selector switch to its proper position depending upon the temperature of the water desired. The operator then rotates the drum switch 107 by means of the knob 121 until the segments 113 and 114 engage the contact fingers 109, 110 and 111, whereupon the main

motor 36, the time switch motor 109 and the valve solenoids 105 and 106 are energized. The main motor circuit includes the line conductor L₁, the finger 110, segment 113, finger 109, a conductor 137, motor 36 and the line conductor L₂. The time switch motor 109 is connected in parallel with the main motor 36 and is energized and de-energized therewith. The circuit for the parallel connected solenoids 105 and 106 include the line conductor L₁, finger 110, segments 113 and 114, finger 111, a conductor 138, solenoids 105 and 106 and the line conductor L₂.

Rotation of the impeller 25 is effected by the main motor 36 and the timer motor 109 operates to rotate the drum switch 108. Water at the selected temperature is delivered to the basket 10 as the valves 103 and 104 are opened by their respective solenoids. Flow of water to the basket 10 continues until the drum switch 108 disengages the segment 114 from the finger 111. The period of time that the valves 103 and 104 are maintained open by the engagement of the finger 111 and segment 114 is sufficient to fill the basket with water to the proper level. Some slight variation in the amount of water delivered to the basket 10 may be caused by variations in water pressure. The operation of my improved washer is not affected by the slight differences in the amount of water delivered thereto that would be caused by pressure variations ordinarily encountered.

It will be understood at this time that the basket 10 is stationary, as the clutch magnet winding 48 is deenergized and, therefore, the clutch elements 44 and 45 are disengaged and the brake 57 is applied.

Agitation of the washing fluid in the chamber 31 is effected by the impeller 25, as described heretofore, for a predetermined period of time determined by the spacing of the segments 114 and 115 of the drum switch 108. At the end of the washing period the segment 115 engages the stationary contact finger 112 whereby the clutch magnet winding 48 is energized through a circuit including the line conductor L₁, the contact finger 110, the segments 113 and 115, finger 112, a conductor 139, the clutch solenoid winding 48 and the line conductor L₂.

Energization of the magnet winding 48 effects engagement of the clutch 43, as described heretofore, whereupon rotation of the basket 10 is initiated. The washing fluid moves outwardly due to centrifugal action and is discharged through the openings 12 into engagement with the baffle 83 and drains to the pan 84. The fluid is discharged from the pan 84 to a point of discharge by means of the pump 85. The fabrics being washed are moved outwardly in contact with the wall 13 of the basket 10 by centrifugal action and a substantial quantity of the washing fluid contained therein is extracted, which fluid passes to the pan 84 as described. Extraction of fluid from the fabrics continues until the contact segment 115 disengages the finger 112 whereupon the clutch magnet winding 48 is deenergized and the clutch 43 is opened. Accordingly the brake 57 is applied and rotation of the basket is terminated.

The contact segment 116 of the drum switch next engages the contact finger 111 for energizing the water valve solenoids. A predetermined amount of rinse water is admitted to the basket and, as the impeller is in operation, the rinse water and fabrics are agitated in the washing chamber. After a predetermined period of oper-

ation, the clutch magnet winding 48 is again energized by the engagement of segment 117 and finger 112 for initiating spinning of the basket. The rinse water is discharged from the basket by centrifugal action and the fabrics are spun for the extraction of rinse water therefrom. After a predetermined period of spinning, the drum switch is moved to its "off" position, wherein both the main motor 36, the timer motor 109 and the clutch solenoid 48 are deenergized. The drum 108 has completed a revolution and is conditioned for another cycle. The fabrics are then removed from the basket for further drying.

The foregoing description relates to one program of steps automatically effected in accordance with the invention, which program may be varied as desired. For example, the fabrics may be given two or more rinsing operations instead of the one described or a spray rinse may be employed during the period of extraction of the wash water.

Throughout the specification, I have referred to drying of the fabrics by centrifugal extraction. In defining the term "drying," I mean the removal of a substantial portion of the fluid from the fabrics or the removal of the amount of fluid that can be removed by conventional centrifugal extractors.

From the foregoing description, it will be apparent that I have provided improved apparatus for washing and drying of fabrics, which apparatus may be manually adjusted for effecting different operations or which may be operated so that the various operations are successively and automatically effected. The washing action and the method of discharging the washing fluid from the apparatus which I employ, permit the design of a washer that is simple and economical to manufacture.

Vibration of the apparatus during the spinning or extracting period is reduced to a minimum due to the substantially uniform distribution of the articles in the basket after the washing period has terminated. This feature of the operation is extremely important when the apparatus is constructed for automatic operation or when the spinning operation is initiated subsequent to the washing operation without manual attention.

I am enabled to employ an extremely simple drive mechanism for the impeller 25 and the basket 10 because the impeller 25 may be continuously rotated and directly connected to the motor shaft. The only adjustment to the drive mechanism during operation is the actuation of a single clutch between the driving motor 36 and the basket 10.

The washing apparatus, as a unit, is substantially symmetrical so that it may be disposed in a casing that is symmetrical and pleasing to the eye. Furthermore, the washing unit may be readily mounted flexibly within the casing so that vibrations originating in the unit are not transmitted to the casing.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. In a machine for washing fabrics and the

like and for extracting water therefrom, the combination of a tub mounted for rotation about a substantially vertical axis and having a bottom wall and a substantially circular vertical wall, said tub embodying a lower sump portion and an upper fabric containing portion and said tub defining the sole container for the wash water in which the fabrics are immersed, said tub also embodying passageway means located adjacent the top of the fabric-containing portion for the ingress and egress of the fabrics and for discharging water from the tub, means for admitting water to the tub, pump means substantially confined in the sump whereby the fabric-containing portion of the tub is substantially unobstructed, said pump means being arranged to discharge water radially against the vertical wall of the tub adjacent the bottom of the fabric-containing portion of the tub, said vertical wall of the tub being effective for deflecting some of said water upwardly after which such water is circulated inwardly toward the center of the tub by the outward motion of the water discharged by the pump means, means for retaining the tub in a fixed position and for driving the pump means during washing periods and means for rotating the tub during water-extracting periods.

2. In a machine for washing fabrics and the like and for extracting water therefrom, the combination of a tub mounted for rotation about a substantially vertical axis and embodying a lower sump portion and an upper fabric-containing portion, said tub defining the sole container for the wash water in which the fabrics are immersed, said tub also embodying passageway means located adjacent the top of the fabric-containing portion for the ingress and egress of the fabrics and for discharging water from the tub, means for admitting water to the tub, pump means substantially confined in the sump whereby the fabric-containing portion of the tub is substantially unobstructed, said pump means including a rotatable impeller and a water discharge nozzle for directing water generally in a horizontal direction adjacent to the bottom of the fabric-containing portion of the tub, whereby the water in the fabric-containing portion is motivated in a toroidal formation, a motor for rotating the impeller, a clutch associated with the tub, and means for actuating the clutch so that the tub is maintained stationary during washing periods and so that the tub is rotated by the motor during water extracting periods.

3. In a machine for washing fabrics and the like and for extracting water therefrom, the combination of a tub mounted for rotation about a substantially vertical axis and embodying a lower sump portion and an upper fabric-containing portion, said tub defining the sole container for the wash water in which the fabrics are immersed, said tub also embodying passageway means located adjacent the top of the fabric-containing portion for the ingress and egress of the fabrics and for discharging water from the tub, means for admitting water to the tub, pump means substantially confined in the sump whereby the fabric-containing portion of the tub is substantially unobstructed, said pump means including a rotatable impeller and a water discharge nozzle for directing water generally in a horizontal direction adjacent to the bottom of the fabric-containing portion of the tub, whereby the water in the fabric-containing portion is motivated in a toroidal formation, a motor for

rotating the impeller at all times that the machine is operated, a clutch connected between the motor and the tub and means for actuating the clutch to a plurality of positions in one of which the tub is maintained stationary during washing periods and in the second of which the tub is rotated by the motor during water-extracting periods.

4. In a machine for washing and drying fabrics, the combination of a container rotatable about a substantially vertical axis, said container having an imperforate bottom portion for containing a body of washing fluid and fluid discharge openings in its upper portion above the normal liquid level of the contained body of fluid, a perforate partition below the liquid level in the container for defining a sump in the bottom of the container, a pump confined substantially in said sump for translating fluid from the sump to the body of fluid above said partition, said translated fluid being projected at relatively high velocity into the body of fluid above the partition for agitating the same, means for rotating the container for centrifugally discharging the body of fluid in the container and fluid from the fabrics through said openings, and means for collecting said discharged fluid.

5. In a machine for washing and drying fabrics, the combination of a substantially cylindrical container for washing fluid, said container having a vertical axis and provided with fluid discharge openings in an upper portion thereof, means for admitting washing fluid to the container, a perforate partition for defining a sump in the bottom of the container, pumping means confined substantially within the sump for withdrawing fluid from the sump and projecting it at relatively high velocity over the upper surface of the partition for agitating the washing fluid in the container, a shaft extending through the bottom of said container for rotating the pumping means, a hollow shaft concentrically disposed about said first-named shaft for rotating the container whereby fluid is centrifugally discharged through said fluid discharge openings, means for collecting the discharged fluid, a motor for rotating said shafts, a clutch connected between the hollow shaft of the container and the motor, a cradle structure disposed below the container for supporting the motor and container, said cradle structure, motor and container being constructed as a unit, and means connected to the cradle structure for supporting said unit.

6. In a washing machine, the combination of a cradle, a basket for washing fluid carried by said cradle and having an imperforate bottom portion and a plurality of fluid discharge ports in an upper portion thereof, means for agitating the fluid in the basket, a motor for effecting continuous rotation of the agitating means relative said basket during all periods of operation of the washer, and means driven by said motor for rotating the basket whereby fluid in the basket is discharged through the fluid discharge ports during drying periods, said motor being supported by the cradle, and means for flexibly supporting the cradle.

7. In a machine for washing and drying fabrics, the combination of a cradle structure, a vertical cylindrical member carried by said cradle structure, a tub for washing fluid journaled on the cylindrical member and having an access opening in the top thereof, said tub having a plurality of fluid discharge ports in a top portion thereof above the normal fluid level in the

tub, means for admitting washing fluid to the tub, an impeller for agitating the fluid in the tub, a shaft for the impeller journaled in said cylindrical member, a motor for driving said shaft and carried by the cradle structure, speed reducing mechanism driven by the motor and including a driven shaft journaled on the cylindrical member, a clutch for engaging and disengaging the tub and said driven shaft, said clutch when engaged effecting rotation of the tub, whereby fluid in the tub is centrifugally discharged through said ports and fluid in the fabrics is extracted therefrom, and means including a trough for collecting fluid discharged from the tub, said trough being supported by the cradle and encompassing said cylindrical member.

8. In a clothes washer, the combination of a tub disposed for rotation about a substantially vertical axis and having its lower portion imperforate for containing washing water and the fabrics immersed therein, said tub having openings formed in the upper portion thereof for the discharge of wash water during periods when the tub is rotated, means disposed adjacent the bottom of the tub for agitating water contained therein, first and second shafts concentrically arranged for driving the agitating means and the tub, respectively, a cradle for rotatably supporting said shafts, a clutch carried at least in part by the cradle and associated with said second shaft and a substantially cylindrical baffle structure encompassing the tub and having an annular trough formed in the depending portion thereof and disposed above the cradle, said trough encompassing, substantially, said shafts and clutch.

9. In apparatus for washing fabrics or the like and for centrifugally extracting water therefrom, the combination of a tub having a lower portion imperforate for containing washing water in which the fabrics are immersed, and including water discharge openings in the upper portion thereof, said tub being disposed for rotation about a substantially vertical axis, means disposed adjacent the bottom of the tub for agitating the water therein, first and second driving shafts concentrically arranged for rotating said agitator and said tub, respectively, a clutch associated with said second driving shaft, a baffle, open at its bottom, encompassing the tub for intercepting water discharged radially through said openings during rotation of the tub and a trough disposed beneath the lower edge of the baffle and encompassing, substantially, the concentric shafts and said clutch.

10. In a clothes washer, the combination of a tub having its lower portion imperforate for containing washing water and the fabrics immersed therein and having openings formed in an upper portion thereof for the discharge of washing water, a cradle structure disposed below the tub for supporting the same so that it may be rotated about a substantially vertical axis, an impeller disposed within the tub adjacent the bottom thereof for agitating the washing water, a shaft for driving the impeller and extending through the bottom of the tub, a fluid-tight seal interposed between the tub and said shaft, means for rotating the tub, a clutch for controlling rotation of the tub, a baffle structure encompassing the tub and having its bottom edge disposed above said cradle structure and a substantially annular trough arranged beneath the bottom edge of said baffle structure for the collection of water discharged from the tub,

said trough being carried by the cradle structure and encompassing the clutch.

11. In apparatus for washing fabrics or the like, the combination of a tub having an imperforate lower portion for containing washing fluid and the fabrics contained therein, said tub having a plurality of fluid discharge openings circumferentially spaced in an upper portion thereof, an impeller for agitating the water in the tub and having a driving shaft extending downwardly through the bottom of the tub, a second shaft concentrically arranged with respect to the first-mentioned shaft for rotating said tub about a substantially vertical axis, said impeller shaft being journaled within the second shaft for rotation with respect thereto, a cradle structure for rotatively supporting both of said shafts, a substantially cylindrical baffle encompassing the tub for deflecting water discharged through said openings downwardly, a substantially annular trough carried by the cradle structure and having a depending portion of said baffle extending therewithin and spaced therefrom, said trough encompassing said first and second shafts, and means associated with said impeller shaft for discharging water from the trough.

12. In a machine for washing and drying fabrics, the combination of a cradle structure, a tub for washing fluid having fluid discharge ports in an upper portion thereof and rotatably supported by and above the cradle structure, a substantially horizontal perforate partition disposed within the tub for defining a sump at the bottom thereof, a pump housing within the sump and provided with fluid passages, said pump housing including a portion above the partition and having a plurality of radially-extending fluid discharge ports formed therein, an impeller in the pump housing, a motor for driving said impeller continuously during all periods of operation of the machine and carried by the cradle structure, a member journaled on the cradle structure and driven by the motor for rotating the tub, and a clutch interposed between said driven member and the tub.

13. In apparatus for washing fabrics and for subsequently extracting water therefrom, the combination of a basket for containing the water and fabrics and disposed for rotation about a substantially vertical axis, an agitator coaxially disposed within the basket, means for continuously rotating the agitator relative the basket in a single direction during both washing and extracting periods, and means for rotating the basket during extracting periods, so that the speed of the agitator relative to the basket is different in the washing and extracting periods.

14. In apparatus for washing fabrics and for subsequently extracting water therefrom, the combination of a basket for containing the water and fabrics and disposed for rotation about a substantially vertical axis, an agitator coaxially disposed within the basket, means for continuously rotating the agitator relative the basket in a single direction during both washing and extracting periods, and means for rotating the basket in the same direction as the agitator during extracting periods so that the speed of the agitator relative to the basket is relatively high during washing periods and relatively low during extracting periods.

15. The combination of a container for cleaning fluid and the fabrics to be treated and disposed for rotation about a substantially vertical axis, means arranged within the container for

agitating the fabrics in the cleaning fluid, driving means for actuating the agitator during washing periods and for rotating the container structure for centrifuging cleaning fluid from the fabrics, said container and driving means being connected and defining a unit structure, and means for flexibly supporting the unit struc-

ture and providing for rocking movement of the unit structure in vertical planes and providing for horizontal translations of the unit structure, said flexible supporting means being effective to restrain the unit structure against vertical translations.

FRANK BRECKENRIDGE.
